UNITED STATES PATENT OFFICE.

NAZARENE MORICI, OF CHICAGO, ILLINOIS.

CARVING OR REPRODUCING MACHINE.

Application filed June 18, 1920. Serial No. 390,005.

To all whom it may concern:

Be it known that I, NAZARENE MORICI, a subject of the King of Italy, residing at Chicago, county of Cook, and State of Illinois, have invented certain new and useful Improvements in a Carving or Reproducing Machine, of which the following is a description.

My invention belongs to that general class of devices known as a carving or reproducing machine which will reproduce a piece of cut, carved or engraved work from a piece of sample work or pattern, and produce the new work in the desired size and an exact copy of the original work or pattern. The invention has among its objects the production of a machine of the kind described which is simple, convenient, compact, durable, reliable, adjustable, efficient and satisfactory for use wherever found applicable. It has particularly as an object the production of a machine by means of which simple or intricate patterns may be reproduced and the machine operated by one who is not a skilled mechanic to reproduce the desired pattern in a perfect and artistic manner. The original pattern or work may be made by a skilled carver, engraver or mechanic, and with this as a pattern the unskilled mechanic can duplicate or reproduce it in the desired relative size and in a minimum of time. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Figure 1 is a view in elevation of the preferred form of my machine;

Figure 2 is a top elevation of the same;

Figure 3 is a sectional view with portions broken away, taken substantially on line 3—3 of Figure 1;

Figure 4 is a sectional view taken substantially on line 4—4 of Figure 3;

Figure 5 is a sectional view taken substantially on line 5—5 of Figure 3;

Figure 6 is a sectional view taken substantially on line 6—6 of Figure 3;

55

Figure 7 is a sectional view taken substantially on line 7—7 of Figure 1;

55

Figure 8 is an end view taken substantially on line 8—8 of Figure 1; and

60

Figure 9 is a view illustrating the operation of the machine on a different type of work from that illustrated in Figure 1.

It may be mentioned that my machine is particularly intended as a reproducing machine, and is, as it is generally known, a carving machine, the carving, however, being done by a rotary drill. In using the machine a pattern P is provided, this being generally made by hand by a skilled mechanic, although the manner of constructing the pattern is immaterial in so far as the present invention is concerned.

65

Referring to the drawings, I provide an adjustable frame which, in the construction shown, consists of side bars 1 and 2, preferably connected at the ends by tie or end members 3, the whole frame being adjustably supported on an arm 4 or its equivalent, which may be mounted as at 5 upon a suitable bench, box or other support for the same. The frame and arm 4 may be of the desired material, size, shape and construction, the size ordinarily depending upon the kind of work for which the particular machine is designed. The machine may be constructed in sizes from a machine of a foot or even less, to the desired number of feet in length. Mounted upon the frame is

70

a head 6 which carries, in the construction shown, a motor 7 or the equivalent source of power arranged to drive shaft 8 (see Fig. 6), which is arranged to transmit power to a drive shaft as will be hereinafter described. In the construction shown, the head 6 is mounted on a head part 9, the parts being secured in place by plate 10 and suitable securing means not shown in detail, such as screws or bolts.

75

Adjustably carried by the frame on each side of the head 6 are adjustable or slidable heads 14 and 15, which are arranged to slidably carry vertically adjustable posts or members 16 and 17, which are preferably made square or in an equivalent manner as the same are not rotatable in the head but only adjustable or movable lengthwise. The

80

85

90

95

100

105

movable post members 16 and 17 are connected through members 22 with the arms 18 and 19 respectively. The arms 18 and 19 are pivotally supported on the head 6 at 20, and are provided with intermeshing gear segments 21 so that the arms will move together, thereby operatively connecting parts 16 and 17 so that vertical movement of one, for example part 16, will be transmitted to move part 17. As shown (see Fig. 4), the brackets or parts 22 are each provided with a stud 23 which pivotally connects the same with the posts 16 and 17, permitting the adjustment of the parts, bars 18 and 19 being arranged to slide in the brackets 22, as will be hereinafter described. Each of the posts 16 and 17 carries a head and other mechanism, and in view of the fact that the heads are similar, a description of one will suffice for both, the same bearing similar reference characters. Referring particularly to Figures 1, 7 and 8, the posts 16 and 17 are formed with forked ends 26 each of which adjustably, or pivotally in the construction shown, carries a head member 27, the head being pivotally supported in the arms 26 of the fork by the shaft 29, and extending part 33 on the head. The head carries a depending frame 28 which is adjustably, as shown pivotally, secured to the head and supported thereby by the studs or shaft portions 31 and 32. The frame portion 28 carries a shaft 35 provided with a chuck 36, which carries a tool or tracer 37 on one head and a drill 37' on the other, which may be secured in place by a thumb screw 38 or equivalent means for the purpose. It will be noted from the preceding description that the members 27 and 28 at the lower ends of the posts 16 and 17 form substantially universal tool carrying heads, as they may be termed, one of which is arranged to carry the tracer, and the other the cutting tool.

As most clearly shown in Figures 3 and 6, the head 6 and frame end members 3 carry a rotatable shaft 39 which extends through the head parts 43 carried by the slidable heads 14 and 15. Shaft 39 is provided with a spiral gear 40 or the equivalent arranged to intermesh with the driving gear 41 on the driving shaft 8. Arranged in the head 43, there being one on each of the movable head parts 14 and 15, is a drive gear 45, which meshes with the gear 46 on a shaft 47 which extends down to the head on the lower ends of each of the posts 16 and 17, and is operatively connected with the carving tool or tracer. It may be mentioned that the gears 45 and 46 are splined to the shafts 39 and 47 so that the head may be moved on the frame and the shaft 47 raised when the posts are raised, as will be described in the operation of the device. Referring particularly to Figures 7 and 8, shaft 47 is provided with a gear 48 meshing with

gear 49 on the shaft 29, which shaft is arranged to drive gear 50, which in turn drives a gear 51 mounted on shaft 32, and this drives gear 52. Shaft 35 is driven from the gear 52 through the bevel gear 53, shaft 54 and gears 55 and 56.

Each of the heads or head parts 43 are connected by rods or shafts 58 and 59, which extend from end to end of the machine and are suitably supported by the head part 6 and frame end members 3. Each head carries depending shafts 60 and 61, which are operatively connected with the head 27 so that movement of one head in any direction will be transmitted to the head on the other post and move it, or control its movements. Inasmuch as the mechanisms are substantially similar, a description of one will suffice for both. Referring particularly to Figures 3 and 4, shafts 58 and 59 are provided with gears 62 which mesh with gears 63 on the shafts 60 and 61. These various gears are splined on the shafts so as to permit adjustment of the parts. The shafts 60 and 61 extend down to the heads 26. Referring to Figure 7, shaft 60 is provided with a gear 66 at its lower end, which is arranged to interengage or mesh with the gear 67 formed on or secured to the extending end of part 33 of the head. The shaft 61 is provided with a gear 68 arranged to intermesh with the gear 69, formed on or provided at the end of shaft 30. Shaft 30 carries a gear 70 which meshes with the gear 71 on shaft 31, shaft 31 being so secured to the frame part 28 that movement of the frame part or shaft, as the case may be, will move the other part.

The heads 14 and 15 are so connected that sliding movement of one head will be transmitted to the other, the connecting means shown being so arranged that the same may be adjusted to give different results. Referring to Figure 1, as well as Figure 2, I have provided threaded rods 74, 75 and 76. These are adjustably connected together at 77-77 so as to substantially provide universal joints. Rod 75 is pivotally carried by a bracket 78 on the head 9 (see Figure 6), while rods 74 and 76 are pivoted to the heads 14 and 15 by internally threaded brackets 79. It will be noted by referring to Figure 1 that two of the rods, for example rods 74 and 75, are oppositely threaded. One of the rods, as shown rod 74, may be provided with a wrench 80 so that adjustment may be varied as desired by rotating the rods as will be hereinafter described. I have shown an adjustable counterweight 82 arranged on the bar 19, the same, however, being secured to the adjacent bracket 82 by means of a tie bar 83, it being understood that any equivalent construction may be employed. In Figures 1 and 2, I have shown a supporting bar or member 85 which may be of the desired size and shape for

slidably supporting or steadyng one end of the frame. The part 85 may be supported or carried in any suitable manner, supports 86 being shown for the purpose. Obviously, similar or equivalent structure may be provided at the opposite end of the frame, should the same be desired. The supports shown may be arranged to not only prevent the sagging of one end but also prevent its raising off of the support.

The operation of the device may be briefly described as follows: Assuming that the parts are set up and adjusted as shown in the drawings. Referring to Figure 1, P represents a pattern to be reproduced, and W a block which is to be finished and be a reproduction of the pattern P. The adjustment is such that the relative sizes of the pattern P and work W will be as desired. The tracer 37 is brought in contact with the pattern, and the drill 37' on the column or post 17 is brought in contact with the block or work W. Obviously, shaft 8 being driven will, through the shafts 39 and 47 and intermediate gears described, drive the tracer 37 on the column 16, and drill 37' on the column 17. The operator moves the tracer 37 over the pattern, bringing the same to every point thereon. As he does so, the vertical movement of the tracer will be transmitted through the rod 16, bar 18, bar 19, post 17, etc., to the drill 37' so that as the tracer is raised or lowered, the drill or carving tool will be likewise raised or lowered. Movement of the tracer from right to left or vice versa will, through the intermediate mechanism, as for example post 16, move the head 14 on the frame, and its movement will be transmitted to the head 15 through the bars or shafts 74, 75 and 76 which move the head 15, which will, through the intermediate mechanism move the carving tool or drill in the opposite direction. The frame bars 1-2 and parts 3, 45 constituting the frame, may be pivoted on its supporting arm 4.

The tracer and tool have substantially a universal movement at the bottom of the columns or posts 16 and 17, as the head 27 may pivot (referring to Fig. 1), permitting the tools to be swung forward or backward while the pivotal connections at 31 and 32 will permit the frame 28 to be swung as indicated by the dotted lines in Figure 1. Obviously, any intermediate position of the drill and tracer may be reached. Movement of the tracer 37 will, therefore, be transmitted through the frame 28, shaft 31, gears 70 and 71, shaft 30, gears 69 and 68, shaft 61, gear 63, gear 62, to shaft 59, and this through the similar train of gears and connecting mechanism at the opposite side will move the drill or carving tool carried by the post 17. Likewise, movement of the head 27 on the post 16 as the marker is

moving forward or backward, will be transmitted from the head 26 through part 33, gear 67, gear 66, shaft 60, gears 62 and 63, to the similar mechanism on the head 15, and down to the tool 37'. The tool will, therefore, be governed in its movements by the movement of the tracer 37; regardless of what the direction of that movement may be. It will be obvious that it is immaterial as to which post carries the tracer and 75 which carries the tool, as the general principle will be the same, the sizes being varied, however, one side of the machine being controlled by the other. I have indicated in the dotted lines in Figure 1 how movement 80 of one head is transmitted by means of rods 74, 75 and 76 to the opposite head. It will be obvious that if it is desired to vary the adjustment of the parts, one shaft, as for example shaft 74, is turned. The threaded engagement of the bracket 79 thereon will vary the distance between the bracket and the joint 77. Rotating the shaft, however, will cause a rotation of shaft 75 which has a threaded engagement with bracket 78, and the shaft being oppositely threaded, the distance between the said coupling 77 and the bracket 78 will be varied. However, rotation of shaft 75 will affect the adjustment 85 of bracket 79 and shaft 76, thereby varying 90 the distance of head 15 from the center head 6.

I have shown the counterbalance 82 for the mechanism adjacent thereto, the same serving to balance the parts at the opposite side of head 6 which, by reason of being a greater distance from the head 6, exert a greater leverage. The counterbalance is preferably connected to the bracket 22 or the equivalent so that as the balance or adjustment desired is secured, the same will be maintained in the mechanisms at the two sides of the machine.

It will be noted that by making the machine so that the marker and tool have substantially universal movements, as described, it is possible to cut or reproduce patterns which would be practically impossible if the tracer and tool had only a vertical and slid- 110 able movement. For example, it is possible to cut under, as indicated at p (see Fig. 1), on pattern P and reproduce this undercut on the work. While in Figure 1 I have shown the work arranged on a table, in Figure 9 I have illustrated how the work 115 may be cut at the sides instead of from the top. Referring to this figure, 82 may represent a column, for example a lamp stand or base which may be set substantially parallel with the post 16 and the tracer T 120 worked along the same from the top to the bottom, and in a similar manner, the work may be placed at the cutting or carving end of the mechanism. While I have particu- 125 larly described the machine as working on 130

work of some size, obviously the parts may be proportioned so that the same may be used by jewelers for reproducing engraving, in which case the machine would be substantially delicate. All this, however, is immaterial as it does not matter what kind of work is to be done nor the material upon which it is to operate nor what the patterns are that are to be reproduced. It is not necessary that a pattern be made before hand as, if desired, instead of a tracer the skilled mechanic can use a drill or cutting tool and while making an original pattern, at the same time produce a reproduction of the same.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

25 What I claim as new and desire to secure by Letters Patent is:

1. In a device of the kind described, a frame, means for pivotally supporting the same intermediate its ends, a plurality of 30 adjustable tool carriers slidably carried by said frame and arranged one on each side of said supporting means, means for driving the tools carried by said tool carriers, and intermediate connecting means between the carriers whereby movement of one will be transmitted to and move the other.

2. In a device of the kind described, a frame, means for supporting the same, intermediate the ends thereof, a plurality of 40 adjustable tool carriers slidably carried by said frame, driving means for the tools carried by said carriers, and intermediate means connecting the carriers arranged to transmit a vertical or transverse movement of one carrier and move the other in a similar manner.

3. In a device of the kind described, a frame, means for pivotally supporting the same between the ends, a plurality of 50 adjustable tool holders, means carried by said frame for slidably and adjustably carrying said tool holders, means for driving the tools carried by said holders, intermediate means between the adjustable tool holder carrying means and the tool holders whereby a vertical or transverse movement of one tool holder will be transferred to the other tool holder.

4. In a device of the kind described and 60 in combination, a frame pivotally supported intermediate its ends, a head member carried by said frame on each side of said supporting means and slidable on the frame, a vertically movable depending post carried by 65 each head, means for connecting said heads

whereby movement of one sliding head will be transmitted to the other, means for operatively connecting said depending posts whereby vertical movement of one will be transmitted to move the other, a universal tool holder head mounted adjacent the lower end of each post and carried thereby, means for operatively connecting said heads whereby movement of one will be transmitted to and move the other, tools carried by said universal heads, and means for driving said tools.

5. In a device of the kind described and in combination, a frame, supporting means therefor intermediate its ends, a slidable 80 head member mounted on said frame on each side of said supporting means, a depending post movably carried by each head, means for connecting said heads whereby movement of one sliding head will be transmitted to the other, means for operatively connecting said depending posts whereby movement of one will be transferred to the other, a universal head mounted adjacent the lower end of each post and carried thereby, means for positively connecting said heads whereby movement of one will be transmitted to and move the other, tools carried by said universal heads, and means for driving one of said tools.

6. In a device of the kind described and in combination, a frame adjustably supported intermediate its ends, a head member carried by said frame on each side of said supporting means and slidable on the frame, a depending post slidably carried by each head, means for connecting said heads whereby movement of one sliding head will be transmitted to the other, means for operatively connecting said depending posts whereby vertical movement of one will be transmitted to the other, a universal head mounted adjacent the lower end of each post and carried thereby, means for operatively connecting said heads whereby movement of one will be transmitted to and move the other, tools carried by said universal heads, and means for driving one of said tools.

7. In a device of the kind described and in combination, a frame, means for adjustably supporting the same, head members carried by said frame one on each side of said supporting means and movable on the frame, a depending post movably carried by each head, means for connecting said heads whereby movement of one head will be transmitted to and move the other, means for operatively connecting said depending posts whereby vertical movement of one will be transmitted to move the other, a universal tool holder carrying head mounted adjacent the lower end of each post and carried thereby, means for operatively connecting said heads whereby movement of one

one will be transmitted to and move the other, a tool holder carried by each of said universal heads, and means for driving one of said tools.

- 5 8. In a device of the kind described and in combination, a frame, a head member arranged intermediate the ends of said frame, means for supporting said head member and frame, a driving shaft carried by said head member, slideable head members arranged on said frame one at each side of said first mentioned head, connecting means between the said slideable head members whereby movement of one will be transmitted to and move the other, a vertically movable post carried by each of said slideable head members, connecting means between said posts whereby vertical movement of one will be transmitted to and move the other, a tool carrier arranged at the lower end of each of said posts and transversely movable thereat in substantially any direction, means for operatively connecting said tool holders whereby a transverse movement of one holder in any direction will be transmitted to and move the other holder a proportionate distance, and means for operatively connecting said power shaft and the tools in said holders.
- 20 9. In a device of the kind described and in combination, a frame, a head member arranged intermediate the ends of said frame, means for supporting said head member and frame, a driving shaft carried by said head member, slideable head members arranged on said frame, one at each side of said first mentioned head, adjustable connecting means between the said slideable head members whereby movement of one will be transmitted to and move the other, a vertically movable post carried by each of said slideable head members, adjustable connecting means between said posts whereby vertical movement of one will be transmitted to and move the other, a tool carrier arranged at the lower end of each of said posts and transversely movable thereon, means for operatively connecting said tool holders whereby a transverse movement of one holder in any direction will be transmitted and move the other holder a proportionate distance, said means comprising shafts carried by the frame, and shafts extending from said sliding heads, and means for operatively connecting said shafts together and to the tool holders, and means for operatively connecting said power shaft and said tool holders.
- 45 10. In a device of the kind described and in combination, a frame, a head member arranged intermediate the ends of said frame, means for supporting said head member and

frame, a driving shaft carried by said head member, slideable head members arranged on said frame one at each side of said first mentioned head, connecting means between the said slideable head members whereby movement of one will be transmitted to and move the other, a vertically movable post carried by each of said last mentioned head members, connecting means between said posts whereby vertical movement of one will be transmitted to and move the other, a tool carrier arranged at the lower end of each of said posts and transversely movable thereon in any direction through an angle substantially greater than 180 degrees, means for operatively connecting said tool holders whereby a transverse movement of one holder in any direction will be transmitted and move the other holder a proportionate distance, and means for operatively connecting said power shaft and said tool holders.

25 11. In a device of the kind described and in combination, a frame, a head member arranged intermediate the ends of said frame, means for supporting said head member and frame, a driving shaft, a slideable head member arranged on said frame at each side of said first mentioned head, adjustable connecting means between the said slideable head members whereby movement of one will be transmitted to and move the other, a vertically movable post carried by each of said slideable head members, connecting means between said posts whereby vertical movement of one will be transmitted to and move the other, a tool carrier arranged at the lower end of each of said posts and transversely movable thereon, means for operatively connecting said tool holders whereby a transverse movement of one holder in any direction will be transmitted and move the other holder a proportionate distance, said means comprising shafts carried by the frame, and shafts extending from said sliding heads, and means for operatively connecting said shafts together and to the tool holders, and means for operatively connecting said power shaft and said tool holders.

50 In testimony whereof, I have hereunto signed my name in the presence of two subscribing witnesses.

NAZARENE MORICI.
